UNITED STATES PATENT OFFICE.

WILLIAM C. GROB, OF TOLEDO, OHIO, ASSIGNOR OF ONE-HALF TO GEORGE B. STORER, JR., OF TOLEDO, OHIO.

WINDOW-CONTROL MEANS.

Application filed February 13, 1922. Serial No. 536,062.

To all whom it may concern:

Be it known that I, WILLIAM C. GROB, a citizen of the United States, and a resident of Toledo, in the county of Lucas and State 5 of Ohio, have made an Invention Appertaining to Window-Control Means; and I do hereby declare the following to be a full, clear, and exact description of the invention, such as will enable others skilled in the art 10 to which it appertains to make and use the same, reference being had to the accompanying drawings, and to the characters of reference marked thereon, which form a part of this specification.

15 This invention relates to control means for drop windows and particularly to means of this class adapted to use in connection with the type of windows commonly used in closed automobiles and other vehicles, which 20 windows have lowering movements when being opened.

The object of the invention is the provision of a control means of the character described which is simple, strong, and durable in its construction, capable of being 25 easily and quickly applied and operable to efficiently lock a glass in any position of adjustment.

The invention is fully described in the 30 following specification, and while in its broader aspect it is capable of embodiment in numerous forms, a preferred embodiment thereof is illustrated in the accompanying drawings, in which,—

35 Figure 1 is a fragmentary vertical section of an automobile door embodying the invention, with the window in lowered position. Fig. 2 is a reduced inner side view of the door with the window lowered and 40 with the inner casing parts removed to expose the window and carrying means. Fig. 3 is an enlarged fragmentary view of a portion of the control means with the connected window partly shown and in section. Fig. 45 Fig. 4 is a section on the line 4—4 in Fig. 3. Fig. 5 is an end view of the channel member 50 of the control means. Fig. 6 is a perspective view of the fiber guide for the window carrying rod. Fig. 7 is an enlarged fragmentary view of a window carrying rod and attached lock bolt. Fig. 8 is a similar view thereof with the upper end of the rod in vertical section. Fig. 9 is a top view of the lock bolt, and Fig. 10 is an enlarged frag-

mentary plan view of one end portion of the 55 window supporting channel.

Referring to the drawings, 1 designates a vehicle having a window opening 2 therein, and 3 a glass or window which is adapted to stand in position to close the opening 2 60 or to be lowered into the lower portion of the door, which is made hollow for such purpose, as is customary in doors used in vehicles, such for instance, as automobiles.

The window glass 3 is fitted at its lower 65 edge into a channel bar 4, preferably formed of sheet metal, such channel being substantially coextensive with the width of the glass and having its upper outer edge turned outwardly to form a stop flange 5. The inner side of the channel-bar has ears 6 struck outwardly from its ends in horizontal position with the ears extending at their outer ends beyond the ends of the bar and each being provided with a longitudinal slot or 70 opening 7 for adjustably receiving the lower end of a carrying rod 8, one of which is disposed at each side of the window glass in inwardly offset relation thereto. The rods are 75 adjustably clamped to the ears by upper and lower nuts 9 threaded thereon.

Each rod 8 extends upward to near the top of the window glass 3 through an opening in the adjacent end of the window sill 10 and is provided at its upper end with a 80 block or head 11, which is mounted for reciprocatory movements in a channeled guide-bar 12. One of these guide-bars is 85 mounted within the window casing at each side and at the inner side of the window glass 3 and is preferably formed from sheet metal, being channel form in cross-section with the outer or free edges of its sides turned inward to form a retracted longitudinal opening 13 in the outer side of the bar throughout its length. Perforated ears 90 14 are struck from one side of the guide bar 12 and extend therefrom in the plane of the channel base and are intended to receive screws 15 for attaching the guide-bars to the respective sides of the window casing. The side of a guide-bar forming the bottom of the channel is provided with a series of longitudinally spaced openings 16 with 95 which the inner end of a lock-bolt 17 carried by the head block 11 may engage to firmly support the rod 8 in any position of its vertical adjustment.

The lock-bolt 17 is mounted for longitudinal reciprocatory movements in the block 11 and has its inner end of stud form for projecting into a registering opening 16, and 5 its outer end projected through the guide bar openings 13 and a distance therefrom to form a handle to facilitate an outward pulling of the lock-bolt to release its locking engagement with the guide-bar and a raising 10 or lowering of the window. The handle end of the lock-bolt is preferably inclined away from the window glass 3 to provide more room for gripping the bolt. The block 11 is slotted as shown at 18, above and below 15 the opening therein through which the lock-bolt projects, a pin 19 projecting with the upper slot from the bolt to prevent a turning of the bolt relative to the block and the lower slot containing a spring finger 20 mounted therein and in engagement with the bolt to normally retain the bolt in inwardly projected position. The inner end of the bolt is preferably tapered as shown 25 to adapt it to be forced out of a guide bar opening 16 when an upward pressure is exerted on the bolt or window, but preventing any downward movement of the window carrying parts until the bolts have been manually withdrawn for such purpose.

30 In order to prevent rattling occasioned by a vibration of the rods 8, each rod projects through a fiber block 21 of felt or other suitable material which is fitted at the lower end of the associated guide bar 12.

35 The lower edge of the glass 3, which seats in the channel bar 4 is bound with felt or other soft fibrous material 22, as is customary in devices of this character, and the flange 5 of the channel bar is provided with a rubber buffer 23, which, when the window is raised to its upward limit, strikes a sill flange 24 at the outer lower edge of the window opening 2. The buffer 23 comprises a bar-like strip of rubber which is slotted to 40 receive the flange 5, and is firmly secured to the flange by cementing the same thereto. This forms a very efficient buffer and one which does not easily become separated from the carrying flange.

45 The weight of the window is at least partially counterbalanced by a lever arm 25, which is pivoted at one end within the interior of the lower portion of the door at one side edge thereof and has its outer end provided with a roller on which the channel 50 bar 4 rests. A coiled tension spring 26 connects the lever to the opposite side edge of the door frame and tends to normally hold the free end of the lever arm in elevated position and to resist a lowering of the window.

55 I wish it understood that my invention is not limited to any specific construction, arrangement or form of the parts, as it is capable of embodiment in numerous forms,

without departing from the spirit of the claims.

Having thus described my invention, what I claim as new, and desire to secure by Letters Patent, is,—

1. In combination, means forming a window casing, a window mounted for vertical reciprocatory movements in the casing, a hollow guide bar secured to a side of the casing lengthwise thereof and having a longitudinal opening in its outer side and a plurality of bolt receiving openings in its inner side spaced longitudinally of the bar, a block mounted in the guide bar for reciprocatory movements longitudinally thereof, so a bolt carried by the block for reciprocatory movements transversely of the guide bar and adapted to have its inner end engage a registering opening in the inner side of the guide bar, the outer end of the bolt extending through the outer opening of the guide bar and forming a handle, a spring carried by the block and acting on the bolt to normally hold it in engagement with a registering opening, and a rod extending down from the block through the guide bar and fixedly attached to the lower edge of the window to cause the window and block to have movements in unison. 70 75 80 85 90

2. In combination, means forming a window casing, a window mounted for vertical reciprocatory movements in the casing, a guide bar secured to a side of the window casing lengthwise thereof and formed of sheet metal bent to form a guide opening longitudinally therethrough which is rectangular in cross-section and having a plurality of longitudinally spaced catch openings in its inner side, a block rectangular in cross-section mounted in the guide bar for movements longitudinally thereof and having a slot therethrough, a catch bolt having a handle at its outer end and a catch stud at its inner end projecting through the outer opening of the bar, the block slot and into a registering opening in the inner side of the bar, the bolt being reciprocally movable in the block transversely thereof, a spring mounted in the block slot and engaging the bolt to normally hold it in inwardly projected position, and a rod extending down through the guide bar and rigidly connecting the lower edge portion of the window and the block. 95 100 105 110 115

3. In combination, means forming a window casing, a window mounted for vertical reciprocatory movements in the casing, a channelled guide bar secured to each inner side of the casing lengthwise thereof and having a longitudinal opening in its outer side and a plurality of vertically spaced lock-bolt receiving openings in its inner side, a block mounted in each guide-bar and guided for reciprocatory movements longitudinally thereof, a bolt carried by the block 120 125 130

60 65 66

for reciprocatory movements transversely thereof, and adapted to have its inner end engage a registering opening in the inner side of the guide bar, the outer end of the
5 bolt extending out through the outer opening of the guide bar and forming a handle, a spring normally retaining the bolt in engagement with a registering opening, a rod extending down from each block through
10 the lower end of the guide bar and fixedly attached to the lower edge of the window at its adjacent side edge to cause the window and blocks to have movements in unison, and a fiber block disposed within the lower end of each guide bar and having an opening through which the respective rod has close reciprocatory movements. 15

In testimony whereof, I have hereunto signed my name to this specification.

WILLIAM C. GROB.
